UNITED STATES PATENT OFFICE.

ABNER F. BUTTRICK, OF EVERETT, MASSACHUSETTS.

HOT-WATER HEATER.

SPECIFICATION forming part of Letters Patent No. 619,542, dated February 14, 1899.

Application filed May 3, 1898. Serial No. 679,612. (No model.)

To all whom it may concern:

Be it known that I, ABNER F. BUTTRICK, a citizen of the United States, residing at Everett, in the county of Middlesex and State 5 of Massachusetts, have invented a new and useful Hot-Water Heater, of which the following is a specification.

My invention relates to hot-water apparatus for heating buildings, and has for its object to economize in the construction of such apparatus and generally improve and simplify such construction.

With this object in view my invention consists in the improved construction, arrangement, and combination of parts constituting a hot-water heating apparatus and a masonry case therefor, all as will be described herein-after and afterward specifically pointed out in the claim.

20 In order to enable others skilled in the art to which my invention most nearly appertains to make and use the same, I will now proceed to describe its construction and operation, reference being had to the accompanying drawings, forming part of this specification, in which—

Figure 1 is a vertical sectional view of my improved hot-water heating apparatus, taken on a plane extending vertically through it 30 from front to rear. Fig. 2 is a sectional view thereof, taken on the vertical plane indicated by the broken line 2 2 of Fig. 1.

Like letters of reference mark the same parts wherever they occur throughout the various figures of the drawings.

Referring to the drawings by letters, A indicates a brick casing, within which is located or embedded my improved hot-water heating apparatus, said brickwork being constructed to form a main chamber B to include the greater part of the apparatus and to form a portion of the fire-box thereof, an opening C leading from the chamber B and being provided with a door D, through which 45 to introduce fuel, and a second opening E, also on the front, leading from below the fire-box, forming the ash-pit and being provided with a door F. A brick partition G is built crosswise of the main chamber, thereby forming a main flue H, with a branch I, leading to the upper part of the main chamber B, and a branch J, leading from the lower part of the

main chamber B, the upper branch I being provided with a damper K, by means of which it may be closed when desired. An opening 55 L extends from the bottom of the flue to the rear of the casing for the removal of ashes and soot and is provided with a door M'. Within the chamber B is located the metallic portion of the apparatus, which consists 60 of a main tank surrounding the fire-box, comprising side chambers N, front chamber O, and rear chamber P to communicate with each other and form substantially a single chamber, the front chamber being of a less 65 height than the rest in order to leave the proper opening in communication with the opening C of the brick casing to receive fuel through the door D. These chambers are connected by tubes or pipes Q, which extend 70 to the upper water-chamber R, which extends entirely over the fire-box. A pipe S leads from the water-supply into the lower part of the side chambers N N, a pipe T from the top of the upper chamber R to the service-pipes and radiators throughout the building, and a return-pipe S' leads from the service-pipes through the building back into the chamber N.

U indicates the grate, and V the metallic 80 plate forming the bottom of ash-pit E.

The construction of my invention will be readily understood from the foregoing, and its operation may be described as follows: A fire being built in the fire-box, the products 85 of combustion will pass through either the direct-draft flue I or the indirect-draft flue J and out of the main flue H, which leads to the chimney, the direction being controlled by opening or closing the damper K by means 90 of its handle K', the draft being turned downward and through the indirect-draft flue J when the damper K is closed. The fire will communicate its heat to the chambers N, O, and P, surrounding it, and in the usual manner, well known, will cause a circulation of 95 the hot water through the pipe T, the service-pipes and radiators, and the return-pipe S', the water in the pipes after having been used through the building being returned to the 100 bottom of the chambers N N and again circulated through the pipe T, all waste being replaced through the pipe S.

While I have illustrated and described

what I now consider to be the best means for carrying out my invention, I do not wish to be understood as restricting myself to the exact forms and constructions shown, but 5 hold that any slight variation therefrom such as might suggest itself to the ordinary mechanician would properly fall within the limit and scope of my invention.

Having thus fully described my invention, 10 what I claim as new, and desire to secure by Letters Patent of the United States, is—

The combination in a hot-water apparatus, 15 with the water-heating chambers, the supply, delivery and return pipes, of the brick casing provided with the main chamber B in

which the water-chambers are located having an opening C, with door D for the introduction of fuel into the fire-box, the ash-pit E, with door F, the main flue H, the direct-draft flue I communicating between it and 20 the upper portion of the main chamber B, the indirect-draft flue J communicating between the main flue and the lower portion of the main chamber C, the cleaning branch L, with door M, and the damper K in the direct-draft flue, 25 substantially as described.

ABNER F. BUTTRICK.
